WILLIS J. PEELLE, OF CHICAGO, ILLINOIS, ASSIGNOR TO CROWN CORK AND SEAL COMPANY, INC., OF NEW YORK, N. Y., A CORPORATION OF NEW YORK

METHOD OF AND MEANS FOR FORMING SCREW CAPS

Application filed July 3, 1929. Serial No. 375,619.

The invention pertains to the making of screw-caps, and more especially to caps of the type disclosed in my prior Patent No. 1,476,918 dated December 11, 1923, in which 5 the skirt is screw-threaded and has formed therein at circumferentially spaced intervals in the thread, enlargements or protuberances adapted to be flattened out to increase the effective circumference of the skirt, and thus 10 permitting its easy removal from the container.

The primary object of the present invention is to provide for the practical and economical manufacture of screw-caps of the 15 character set forth.

I attain this object by rolling the skirt of the cap between two revolving dies operating to form the screw-threads and protuberances simultaneously, the circumference of the dies 20 being such that for each revolution of the cap the dies rotate through a distance which is greater than one revolution by the difference between the circumferences of the dies and the cap.

25. In the accompanying drawings,

Figure 1 is an elevational view of two coacting dies operating upon a cap, the latter being shown partially in section.

Fig. 2 is a view showing the dies in edge 30 elevation with the cap being operated upon shown in section.

Fig. 3 is a view showing in perspective the two coacting dies detached.

Fig. 4 is an underside perspective view of 35 a cap formed in accordance with the invention.

Fig. 5 is a plan view illustrating one method of mounting the dies.

40. In the illustrative embodiment of the invention, the cap to be formed comprises a main or top wall 7 having a peripheral flange 8 equipped with a rounded thread having a top 9 and a bottom 10 (Figs. 2 and 4). At 45 spaced points throughout the circumference of the cap, interposed in or interrupting the thread, are a plurality of enlargements or protuberances 11. The latter in the present instance are of a length such as to extend in 50 a direction parallel with the axis of the cap

a distance sufficient to bridge two adjacent convolutions of the thread.

In forming the screw-thread together with the enlargements or protuberances, a previously shaped blank having a plain skirt 8 with a beaded peripheral edge is placed between two opposed dies 12 and 13 suitably mounted upon a machine frame 14 and adapted to be driven in opposite directions at uniform speed. One of the dies, as for example the die 13, may be mounted for movement toward and from the other die through the medium of a sliding head 15, the head 16 for the stationary die being fixed. 17 and 18 designate gears through the medium of which both dies may be rotated.

The dies 12 and 13 as shown in Fig. 1 are made of equal diameter and have their peripheral surfaces shaped to provide coacting screw-thread-forming ribs and grooves helically disposed (Fig. 2). At equidistantly spaced points in the periphery of the die 12 are a plurality of bosses or projections 19 approximately of a length equal to the thickness of the die and thus extending across the bottoms and tops of the screwthread-forming grooves and ribs. Similarly, the die 13 is provided with equidistantly spaced recesses 20 adapted to receive the projections 19. The latter may be formed integrally with the die 12 or may be formed separately and secured in notches 21 formed in the periphery of the die 12.

It will be observed from Figs. 1 and 2 that the dies 12 and 13 are of a diameter somewhat less than that of the cap skirt 8, and the difference in circumference is in the present instance equal to the length of the segment between two adjacent projections 19, or between two adjacent recesses 20. The result of this arrangement is that the die 12 with its projections 19 is adapted to receive freely a blank cap to be formed, and upon the completion of the forming operation to permit the cap to be removed readily.

In the forming operation the dies rotate through a distance which is greater than one revolution by the length of the segment between two projections 19 or recesses 20, in order to effect one complete revolution of the 100

cap. Accordingly the portions of the dies which form the first protuberance also form the last protuberance, and the screw-threads formed in the segment between said protuberances are formed by the same portions of the dies that form the initial portion of the thread. As a result a slight distortion occurs at the end of the thread, or, in other words, a true helical thread is not formed. 5
10 In work of this class, however, the permissible tolerances are so large that the slight distortion occurring is negligible especially when the portion thus distorted is small as compared to the entire circumference of the cap as is the case when a relatively large number of protuberances are formed. 15

The foregoing operation may be repeated to effect a second complete revolution of the cap. This is preferable in order to insure the proper formation of the protuberances, and as to the threads, the latter are merely reformed to conform to the changed positions of the dies relative to the cap. 20

I claim as my invention:

25 1. An apparatus for forming screw-caps comprising a pair of circular rotatable dies between which the skirt of the cap is to be rolled, said dies having peripheral thread-forming portions with spaced coacting projections and recesses interposed at spaced intervals in the thread-forming portions, and said dies having a circumference which is less than the circumference of the cap by the distance between two of said projections. 30

35 2. An apparatus for forming screw-caps comprising a pair of circular rotatable dies between which the skirt of the cap is to be rolled, said dies having peripheral thread-forming portions with equally spaced coacting projections and recesses interposed at spaced intervals in the thread-forming portions, and said dies having a circumference which is less than the circumference of the cap by the distance between two adjacent projections. 40

45 3. An apparatus for forming screw-caps comprising a pair of circular rotatable dies between which the skirt of the cap is to be rolled, said dies having their peripheral surfaces shaped to form a screw-thread in said skirt with spaced enlargements in the thread, and said dies further being of equal size and having a circumference which is less than the circumference of the cap skirt by the distance between two enlargements. 50

55 4. The method of forming a screw-cap for jars and the like which consists in rolling the skirt of the cap between two revoluble dies of equal size and of less diameter than the cap to form simultaneously a screw-thread and plurality of protuberances spaced apart a distance corresponding to the excess in the length of the circumference of the skirt as compared to the circumference of the 60 dies. 65

5. The method of forming a screw-cap for jars and the like which consists in rolling the skirt of the cap between two revoluble dies of equal size and of less diameter than the cap to form simultaneously a screw-thread and plurality of protuberances spaced apart a distance corresponding to the excess in the length of the circumference of the skirt as compared to the circumference of the dies, and limiting the extent of rotation of the dies approximately to two complete revolutions of the cap. 70
75

In testimony whereof, I have hereunto affixed my signature.

WILLIS J. PEELE.
